UNITED STATES PATENT OFFICE

HARRY E. CAMPBELL, OF BALTIMORE, MARYLAND, ASSIGNOR TO CAMPBELL METAL WINDOW CORPORATION, OF BALTIMORE, MARYLAND, A CORPORATION OF MARYLAND

WINDOW HEAD CONSTRUCTION

Application filed November 5, 1929. Serial No. 404,893.

According to the present invention, I provide a weather-tight joint between the upper sash of a window and the lintel by forming the lintel in box-like shape, with an opening 5 in its lower surface to receive the edge of the sash and by providing a member adjacent such opening which carries a flexible weather strip to engage the edge of the upper sash. Such an arrangement is particularly valuable 10 in connection with a window of the type in which an enlarged chamber is provided back of each jamb into which the edges of the upper sash extend, for the lintel construction can be carried across to the full width of the sash 15 so that there is a seal at the corners of the sash as well as in the part over the window opening.

My invention can readily be understood by the illustrative example herein described which shows the same applied to a type of 20 window such as is shown in a number of my earlier patents such, for example, as Patent No. 1,549,711, issued August 11, 1925.

In the drawings which accompany this specification, Fig. 1 is a perspective view of 25 an upper corner of a window frame and sash with the lintel and upper sash member shown in section; Fig. 2 is a perspective view similar to Fig. 1 but with the parts shown in different position, and Fig. 3 is an elevation of the same 30 upper corner showing the sash in place, but with the lintel only partly assembled.

The upper sash 10 has side plates as indicated at 12 and a top plate 14. The plates 12 and 14 are bent to form glass rabbets 16. 35 The top glass stop 18 is bent inwardly, upwardly and again outwardly to form the projection 20, which limits the upward movement of the sash.

The side plates 12 extend through openings 40 as indicated at 22 into enlarged chambers the outer wall of which is formed by the partition member 24. The box-like lintel is formed of two members, one of which, 26, forms the inner face and a portion of the lower face which is inside of the upper sash, and is also bent upwardly at the outside to 45 form a contact member 28. The other main lintel member 30 forms the balance of the lower face, the outer face and the upper face of 50 the lintel. An opening is left between the

member 28 and the inside edge of the bottom part of member 30 to receive top plate 14 of the sash. A flexible weather strip 32 is slipped over the top of portion 28 of member 26 and is held in place on member 28 by 55 member 30. When the upper sash is closed, plates 14 will strike flexible weather strip 32 and deflect it outward but a tight seal will be had between this weather strip and the plate 14. It is to be noted, as shown in Fig. 3, 60 that portion 28 of member 26 and the weather strip 32 both extend over to meet partition 24 which is the outer limit of the enlarged chamber into which the side of the sash extends so that weather strip 32 seals over the side of the 65 sash which is inside the jamb as well as sealing the part which is exposed when the window is open.

This is a very inexpensive construction to put together and is highly efficient in operation. 70

What I claim is:

1. In a window of the type having jambs and openings in the inner wall of the jambs, enlarged chambers back of such openings and 75 an upper sash having side portions adapted to extend through such openings into such chambers, a hollow lintel connecting the jambs having an opening in its lower face substantially in line with the opening in the inner jamb walls for the upper sash, an upwardly extending plate in the lintel adjacent such opening, a flexible weather-strip member carried thereby but flaring away from such plate near its lower edge, and a top 80 portion on the upper sash adapted to enter said lintel opening and contact with said weather-strip to deflect the same away from said plate. 85

2. A structure as specified in claim 1, in 90 which said plate and weather strip are as long as the width of the upper sash.

3. A structure as specified in claim 1 in 95 which said weather-strip embraces the upper edge of said plate and is held in place by the cover member of the hollow lintel.

4. A structure as specified in claim 1, in 100 which said plate is on the room side of said lintel opening so that the tension of said

weather-strip will press the upper sash towards such room side.

5. In a window of the type having jambs and openings in the inner wall of the jambs, 5 enlarged chambers back of such openings and an upper sash having side portions adapted to extend through such openings into such chambers, a hollow lintel connecting the jambs having an opening in its lower face 10 substantially in line with the opening in the inner jamb walls for the upper sash, an upwardly extending plate in the lintel adjacent such opening, a flexible weather strip member of U-shaped cross section looped over the 15 edge of said plate, said member being positioned so that one of its sides is substantially in line with the lintel opening and adjacent said plate, but said side at its lower edge flaring away from said plate, at top portion upon 20 said sash adapted to enter said lintel opening and slidingly contact with the said weather strip member and enter between the strip and the plate whereby the weather strip member is forced away from the plate and the sash 25 member is tensioned towards the plate.
